BACKPACK TRANSMITTER OR SIMILAR ARTICLE

Cornelius T. de Kam, Edgewood, Pa., assignor to
Westinghouse Air Brake Company, Swissvale, Pa.

Filed Oct. 28, 1969, Ser. No. 19,768

Term of patent 14 years

Int. Cl. D14—03

U.S. Cl. D26—14

Fig. 1.

Fig. 2.

FIG. 1 is a front perspective view of a backpack transmitter or similar article showing my design; and

FIG. 2 is a rear elevational view thereof with portions omitted for ease of illustration.

I claim:

The ornamental design for a backpack transmitter or similar article, substantially as shown and described.
